UNITED STATES PATENT OFFICE.

JAMES M. JACKSON, OF CANNON, TEXAS.

COUPLING FOR SEWING-MACHINES.

SPECIFICATION forming part of Letters Patent No. 749,295, dated January 12, 1904.

Application filed October 2, 1903. Serial No. 175,517. (No model.)

To all whom it may concern:

Be it known that I, JAMES M. JACKSON, a citizen of the United States, residing at Cannon, in the county of Grayson and State of Texas, have invented a new and useful Coupling for Sewing-Machines, of which the following is a specification.

This invention relates to devices employed for the purpose of preventing shafts from being rotated backward, and is more particularly applicable to sewing-machines to prevent them running backward and breaking the thread, and has for its object to simplify and improve devices of this character.

15 The invention consists in certain novel features of construction, as hereinafter shown and described, and specified in the claims.

In the drawings illustrative of the invention, in which corresponding parts are denoted 20 by like designating characters, Figure 1 is a side elevation of a portion of a sewing-machine with the improvement applied. Fig. 2 is an enlarged sectional detail of the same. Fig. 3 is a transverse section on the line 3 3 of Fig. 2. Fig. 4 is a perspective view of the coupling-sleeve detached.

25 The improved device may be applied to any suitable part of the driving mechanism of a sewing-machine, but will preferably be applied to the main drive-wheel and its shaft, and for the purpose of illustration it is shown thus applied, 10 representing the table supported upon the frame 11 and carrying the usual "head" 12 for the mechanism above the table and with the usual belt-pulley 13.

The main drive-pulley is represented at 14 and mounted rigidly upon a shaft-section 15, supported for rotation in the frame 11.

Extending from the frame 11 is a bracket 40 16, supporting a shaft-section 17 in longitudinal alinement with the shaft-section 15 and one section preferably with a stud 18 engaging a recess or socket in the adjacent end of the other shaft-section, as shown. The shaft-sections are thus independently rotative in their bearings.

The pulley 13 is driven from the pulley 14 by the cord belt 19, and the shaft-section 17

is provided with a crank-wheel 20, to which the usual pitman 21 is applied, as shown in Fig. 1.

Slidably disposed upon the shaft-sections 15 17 is a sleeve or collar 22, extending for a considerable distance over the adjacent portions of each section and forming a shield and support for the joint between them, as shown. 55

The sleeve 22 is provided with one or more elongated longitudinal apertures 23, through which pins 24 extend from the shaft-section 15, and the opposite end of the sleeve is provided with one or more recesses 25 with one side inclined and adapted to engage projections 26 on the shaft-section 17. 60

A spring 27 is disposed on the shaft-section 15, bearing against the sleeve 22 and maintaining it yieldably in engagement with the projections 26. 65

As many of the apertures 23 and pins 24 and recesses 25 and projections 26 may be used as required; but generally sets of each, as 70 shown, will be sufficient.

When thus constructed, it will be obvious that when motion is imparted to the crank-wheel 20 in a forward direction the projections 26 will engage the straight sides of the recesses 25 and carry the sleeve 22 with it, which in turn will carry the shaft-section 15 by the action of the pins 24 in the slots 23, the sleeve being kept up to its work by the spring 27. 75 When, however, the motion of the crank-wheel is reversed, the projections 26 will run over the inclined sides of the cavities 25 and move the sleeve longitudinally of the shaft-sections by compressing the spring 27, but without rotating the shaft-section 15. 80 By this simple arrangement when the drive-crank wheel 20 and its connected drive-shaft section 17 are rotated forwardly they will "pick-up" and carry the driven shaft-section 15 and its attached pulley with it, and when 85 the motion is reversed the projections 26 will merely "click" over the recesses 25 and not rotate the drive-pulley. Thus when attached to a sewing-machine the latter can be driven only in one direction, which is a very desirable feature, as no danger then exists of break- 90 95

ing the thread by running the machine backward, as with a sewing-machine thus equipped it is impossible to run the machine backward.

The elongated sleeve 22, extending over 5 and closely engaging the adjacent ends of the shaft-sections 15 17, performs the twofold function of a means whereby the motion is transmitted from the shaft-section 17 to the shaft-section 15, but also as a support and 10 shield to the abutting ends of the two sections and materially assist the frame 11 and bracket 16 to support them.

Having thus described the invention, what I claim is—

15 1. In a device of the character described, a shaft in two sections mounted in longitudinal alinement for independent rotation, a sleeve slidable upon said shaft and rotative with one of said sections and provided with one or 20 more cavities in one end inclined upon one side, projections carried by one of said shaft-sections for engagement with said cavities, a spring bearing against said sleeve and maintaining it yieldably in engagement with said 25 projections, means for applying motion to one of said shaft-sections, and means for transmitting motion from the other of said shaft-sections, whereby motion will be imparted to said driven section only when the driving-section is rotated in one direction, substantially 30 as described.

2. In a device of the character described, a supporting-frame, a shaft in two sections and mounted in longitudinal alinement for independent 35 rotation in said frame, a sleeve carried by said shaft-sections and having one or

more longitudinal apertures and with one or more recesses in one end inclined on one side, pins carried by one of said shaft-sections and extending through said apertures, projections carried by the other of said shaft-sections for engagement with said recesses, a driving-pulley carried by one of said shaft-sections and having a spring thereon between said driving-pulley and sleeve, means for applying motion to one of said shaft-sections, and means for transmitting motion from the other of said shaft-sections, substantially as described. 40 45

3. In a device of the character described, a supporting-frame, a shaft in two sections and mounted in longitudinal alinement in said frame for independent rotation, a sleeve carried by said shaft-sections and slidable thereon and forming a support for their adjacent ends and provided with one or more longitudinal apertures and with one or more recesses in one end with one inclined side, pins extending from one of said shaft-sections through 50 said aperture, projections carried by the other of said shaft-sections for engagement with said recesses, and a spring bearing against said sleeve and maintaining it yieldably in engagement with said projections, substantially as described. 55 60 65

In testimony that I claim the foregoing as my own I have hereto affixed my signature in the presence of two witnesses.

JAMES M. JACKSON.
